HENRY M. RUSSELL, JR., OF WHEELING, WEST VIRGINIA.

CLOSURE FOR COLLAPSIBLE TUBES AND THE LIKE.

1,081,555.

Specification of Letters Patent. Patented Dec. 16, 1913.

Application filed February 10, 1912. Serial No. 676,922.

To all whom it may concern:

Be it known that I, HENRY M. RUSSELL, Jr., of Wheeling, Ohio county, West Virginia, have invented a new and useful Improvement in Closures for Collapsible Tubes and the like, of which the following is a description, reference being had to the drawings, forming part of this specification, in which—

10 Figure 1 is a longitudinal section of one form of my invention; Fig. 2 is a similar section of this form after it has been broken and the relative position of the parts has been changed; Fig. 3 is a view of a slightly 15 different form of the invention; and Fig. 4 is a section of this form after it has been broken and the relative position of its parts has been changed.

My invention relates to closures for collapsible tubes such as are made from soft metal on a press by the extrusion process.

Among the objects of my invention are to provide a closure which will be hermetically sealed during shipment and until once 25 opened by the consumer, which will be easy to open without tools and when once opened may easily be temporarily closed and which can be formed in solid dies on presses now used for making collapsible tubes and 30 which, if desired, can be formed during the operation of making the tube.

My invention consists of a hollow neck attached to the tube or other container and threaded on the inside. A threaded stopper 35 is attached to the neck in such a way as to close the latter. The connection between the neck and the stopper is very thin so that the stopper may be broken off leaving the neck open, and afterward reversed and 40 screwed into the neck to close it temporarily.

Referring now to the figures: Fig. 1 is a longitudinal section of the simplest form of my invention as applied to a collapsible tube. Fig. 2 is a longitudinal section of the 45 same form after the stopper has been broken off and screwed into the neck. In both these figures the numeral 4 refers to a fragment of the body of the collapsible tube, and 5 denotes the breast of the tube.

50 The numeral 6 designates the neck portion; 7 is a cylindrical portion of the closure of smaller diameter than the neck 6; and 8 is the threaded portion of the stopper.

Fig. 3 is a view of a slightly different 55 form of the improved closure and Fig. 4 is a

longitudinal section of this form after the stopper has been broken off and screwed into the neck.

In Figs. 3 and 4 the numeral 9 designates the breast of the collapsible tube; 10 is the neck; 11 is a cylindrical portion of the closure of smaller diameter than the neck; 12 is the threaded portion of the stopper; and 13 is a groove in this portion designed to furnish a temporary opening when the stopper is screwed part way out. For containers of the kind to which this improvement is applicable, such as collapsible tubes, it is desirable to have a closure that may be formed completely or largely in the same 65 operations by which the tube itself is formed. On account of the very high pressures required to form the tubes, it would be very difficult, if not impossible, to use a split die. So the closure should be of such 70 form that it can be made as nearly complete as possible in the die which forms the tube and this die must be solid—that is without any longitudinal seams or joints. To accomplish this, each part of the closure must 75 be capable of being withdrawn through those parts of the die which formed the outside of any parts of the closure nearer to the tube. Likewise, the closure must be capable of removal without deformation 80 from the solid punch which formed the interior of it and of the tubes. Now it is plain that if we thread the outside of the neck in the usual way and make integral with the neck a cap that will fit these threads, we 85 90 cannot under the above limitations form a groove between the two that will allow them to be easily broken apart. Even when we reverse the threads, threading the neck internally and the stopper externally, we can- 95 not form a circular groove either inside or outside between the two threaded portions. But I contract the neck below the top of the internally threaded hole in it, to a cylinder 100 of a diameter that only misses the thread groove by a small distance. This gives me a very thin wall all the way around on a helical line, which makes the closure breakable and fulfills all the conditions above set forth.

105 Looking at Fig. 1 it is plain that the closure is of such a shape that it may be screwed out of the die that formed the outer surface and off the punch that formed the inner surface leaving everything intact, pro-

vided only the punch be rotatable with respect to the die.

The form shown in Figs. 3 and 4 shows some variations. First, the shoulder at the top of the neck 10, where the contracted portion 11 starts, is not level but is helical in form so that it follows the thread groove. This tends to give a smoother break. There is also a groove 13 in the threaded portion 10 of the stopper. This forms an opening when the stopper is only partly unscrewed so that the stopper need not be removed and is less liable to loss. It also forms an oblong opening if desired so that the contents will issue in the form of a ribbon. These two variations have no necessary connection. Either may be applied without the other. To make the groove one additional operation would probably be used. Either the groove or the external threads would be made in the solid die and the one not so made would be cut afterward.

I have laid stress on the methods of manufacture, because the characteristics of the closure which make it easy to manufacture are as important parts of my invention as those which enable it to perform its functions.

In the claims certain threads are said to correspond to certain other threads. By this is meant that one of the threads is an external thread and the other an internal one and that they are either both right handed or both left handed and that the pitch and other dimensions are equal. In other words two threaded parts are spoken of as "corresponding" when one will fit into the other like a bolt into its nut.

I claim:

40 1. A collapsible tube formed of soft metal and comprising a body, a breast integral with one end of said body, a neck integral with said breast, a tip formed integral with said neck and of smaller diameter than said neck, the outer end portion of said tip being screw-threaded, a similarly screw-threaded opening being formed in said neck, said opening extending through the neck and into the adjacent end of the tip, whereby the

juncture between the neck and the tip is 50 weakened.

2. A collapsible tube formed of soft metal and comprising a body, a breast integral with one end of said body, a neck integral with said breast, a tip formed integral with 55 said neck and of smaller diameter than said neck, whereby a shoulder so formed between the neck and the tip, said shoulder being helical, the outer end portion of said tip being screw-threaded, a similarly screw-threaded opening being formed through said neck, said opening extending into the adjacent end of the tip, whereby the juncture between the neck and the tip is weakened. 60

3. A collapsible tube formed of soft metal and comprising a body, a breast integral with one end of said body, a neck integral with said breast, a tip formed integral with 65 said neck and of smaller diameter than said neck, the outer end portion of said tip being screw-threaded, a similarly screw-threaded opening being formed in said neck, said opening extending through the neck and into the adjacent end of the tip, whereby the juncture between the neck and the tip is 70 weakened, and a part of the threaded portion of the tip being longitudinally grooved to form an outlet. 75

4. A collapsible tube formed of soft metal and having an internally threaded neck, and 80 an externally similarly threaded tip integral with said neck, the junction between the neck and the tip being weakened by the internal threads, whereby the tip may be broken off and screwed into the neck. 85

5. A collapsible tube formed of soft metal and having a hollow internally threaded neck and an externally similarly threaded tip integral therewith, the tip being of 90 smaller diameter than the neck and the hollow of the neck extending beyond the junction of the neck and tip, whereby the latter may be broken from the former, at the juncture.
